SPOOL DISPLAY DEVICE

Alfred Ogden, Pawtucket, R. I., assignor to J. & P. Coats (Rhode Island) Incorporated, a corporation of Rhode Island

Application January 28, 1931. Serial No. 511,671

7 Claims. (Cl. 312—45)

This invention relates to a display device particularly for such articles as spools of thread, and has for its object the vertical display of the spools throughout their length, and at the same time preventing discharge of the spools by a movement at right angles to their axes.

Another object of the invention is the display of the spool in such a manner that it will be held in place against accidental removal, but will permit the spool to be manually lifted from place without engaging the threads thereon.

Another object of the invention is the provision of a plurality of tubes which are so cut at their lower edge as to retain the spools in place against removal at right angles to the extent of the tube, but which will permit removal by manually manipulating the spool to position at a certain angle at which discharge is permitted.

A further object of the invention is the provision of a construction for quickly and economically securing the upper edge of a magazine tube in place, which at the same time will prevent accidental discharge of the spool from the top thereof, such as might occur in shipping or the like.

A still further object of the invention is the provision of a device supported in an easel-like fashion which may have advertising material carried thereon and of such shape as to enhance the appearance and attractiveness of the device.

With these and other objects and advantageous features in view, the invention consists of a novel arrangement of parts more fully disclosed in the detailed description following, in conjunction with the accompanying drawing, and more particularly set forth in the appended claims.

In the drawing:

Fig. 1 is a front elevational view of the device;

Fig. 2 is a side elevation thereof showing the easel-like manner of supporting the same;

Fig. 3 is a section on line 3—3 of Figure 1;

Fig. 4 is a fragmental detail of the face plate of the easel showing the fingers as cut from the stock thereof which engage the tube.

In the sale of spools of thread or other articles, it is of advantage to display the article at full length, especially is this true where various colors of thread are displayed that matching of the colors may be facilitated. It is also desirable to mount the spools so that they may be removed by engagement with the lower head of the spool and without the necessity of handling or touching the thread itself; and in order to accomplish this result, I have mounted in close relationship a plurality of tubes upon the face plate of an easel support with a flange extending from the face plate beneath the spools, and have cut the ends of the tubes at an angle so that the upper end or head of the spool is held against movement at right angles to the axis of the tube, whereby

the spool cannot be removed by a right angular movement, but can be removed by engaging the lower head and sliding the same outwardly from the flange until beyond the edge thereof, whereupon the same may be moved downwardly and withdrawn by the fingers, and upon such withdrawal a succeeding spool will drop into display position. It is also desirable in such a device to prevent the spools from being discharged from the upper end of the tube which I have accomplished by the use of a finger extending into the tube for holding the same in place, the edge of which at the same time serves as an abutment to engage the upper end of the spool to prevent its removal from the upper end of the tube. This finger, although of such thickness as to prevent the discharge of the spool from the upper end will permit a spool to be crowded past the finger for loading the tube; and the following is a detailed description of the present embodiment of this invention, illustrating the preferred means by which these advantageous results may be accomplished.

With reference to the drawing, 10 designates the face plate which is supported in an easel-like fashion by a pair of wing supports 11 hinged to the back of the plate and held in the relation shown in Figure 2 by means of a locking tongue 12 which extends at right angles to the plane of the wing supports 11 and engages notches 13 in the wing supports when in locking position.

A plurality of tubes 14 are secured to the front of the face plate 10 by staples 15 at the lower edge of each tube, and a finger 16 cut from the stock of the face plate 10 and bent over the upper edge 17 of the tube and extending thereinto. A flange 18 extends outwardly from the lower edge of the face plate 10 upon which rests the lowermost spool 19 of a series of spools 20, 21, 22 and 23, each resting upon the next spool 100 below it and housed in the tube to act as a supply magazine for the display.

Each tube is cut on an angle as illustrated at 25, the angle with relation to the axis of the tube being substantially an angle which would be formed relative to the axis of a spool by a line extending from a point on the upper head of the spool to a point diametrically opposite therefrom on the lower head of the spool and which is substantially indicated by the dotted line indicating the line of cut as shown in Figure 3. The end of the tube being so formed, exposes to view the full length of the spool from end to end and the thread thereon, and the opening being of a restricted character as at 26 will prevent the upper head of the spool and consequently the spool from being removed from the tube at right angles to the general extent thereof, and which with the weight of the spools above holding it against the flange, will prevent the spool 120

from being accidentally discharged from the device in ordinary handling or shipping. The lowermost spool 19, however, must be removed by moving its lower head 27 as a designated in Figure 3, outwardly along the flange 18 until clear at the flange 18 as shown in the dotted line position and at an angle to the tube, the spools above being lifted upwardly slightly by the angular position of the lower spool, whereupon this lowermost spool 19 may be withdrawn or moved downwardly and the next spool 20 above will be permitted to drop into its position.

The discharge from the upper end of the device is prevented by the edge 28 of the finger 16 which forms an abutment preventing upward movement of the upper spool 23 and consequently the magazine of spools therein, although there is sufficient resiliency between the parts to permit the magazine to be loaded with spools by forcing them into the top end 29 of the tubes.

The plate 10 extends upwardly beyond the top of the tubes and may have advertising or display parts thereon such as a spool 30 secured to the plate and extending above for ornamental purposes.

It will thus be apparent that I have provided a device which may display the spools their full length and in which the spools will not be discharged accidentally from either end thereof, but which may be easily lifted from place by engaging the lower head of the spool without touching the thread thereon to lift the same from position, after which the spool next above in the magazine will drop in place.

It will also be apparent that the tubes may be of different diameters to accommodate larger or smaller diameter spools of varying sizes and may be used upon a single display arranged symmetrically in graduated relation.

While I have described certain construction forms which embody the principles of my invention, it is obvious that other desired changes in arrangement may be made within the spirit and the scope of the invention as defined in the appended claims.

I claim:

1. In a display device, a plate, a tube cylindrical in cross section mounted on said plate for receiving articles generally the shape of the tube, said tube being cut at an angle to its axis at its lower end, a flange extending from said plate upon which articles in the tube may rest and be supported, said angular cut and said flange being so arranged as to cooperate to prevent an article in its tube and resting on said flange from being removed in a direction at right angles to the axis of its tube, but permitting removal by sliding the end of the article along the flange away from the plate to incline the axis of the article to the axis of the tube until beyond the edge of the flange, whereupon it might be withdrawn from the tube.

2. In a display device, a plate, a plurality of tubes cylindrical in cross section mounted on said plate for receiving articles generally the shape of the tube in which received, said tubes each being cut at an angle to its axis at its lower end, a flange extending from said plate a distance less than the diameter of the tube upon which articles in the tubes may rest and be supported, said angular cut and said flange being so arranged as to cooperate to prevent an article in its tube and resting on said flange from being

removed in a direction at right angles to the axis of its tube, but permitting removal by sliding the end of the article along the flange away from the plate to incline the axis of the article to the axis of the tube until beyond the edge of the flange, whereupon it might be withdrawn from the tube.

3. In a display device, a plate, a tube cylindrical in cross section mounted on said plate, a flange extending from said plate beneath said tube and adjacent the end thereof, said tube being adapted to receive a plurality of spools with the lowermost resting on said flange, said tube being cut at an angle to its axis from a point on the front of the tube above the flange substantially the height of the spool to be received to the end of the tube adjacent the lower end of the spool, whereby the lowermost spool is fully displayed and held in position against removal at right angles to the axis of the tube.

4. In a display device, a plate, a tube cylindrical in cross section mounted on said plate, a flange extending from said plate beneath said tube and adjacent the end thereof, said tube being adapted to receive a plurality of spools with the lowermost resting on said flange, said tube being cut at an angle to its axis, said angle to the axis being substantially the angle to the axis of the spool to be received made by a line from a point on the periphery of one end to a diametrically opposite point on the periphery of the other end of the spool.

5. In a display device, a plate, a tube cylindrical in cross section mounted on said plate, a flange extending from said plate beneath said tube and adjacent the end thereof, said tube being adapted to receive a plurality of spools with the lowermost resting on said flange, said tube being cut at an angle to its axis, said angle to the axis being substantially the angle to the axis of the spool to be received made by a line from a point on the periphery of one end to a diametrically opposite point on the periphery of the other end of the spool, the top edge of the angular cut being substantially the distance from said flange of the height of said spool.

6. In a display device, a plate, a plurality of tubes cylindrical in cross section and open at their upper ends mounted on said plate for receiving articles generally the shape of the tube, means at the end of the tube for displaying an article in the tube and preventing it from being removed in a direction at right angles to the tube, but permitting removal of the article by its lower end being moved outwardly to incline it to the axis of the tube, and yielding fingers extending over a portion of the upper end of each tube to permit insertion of the article but prevent its removal.

7. In a display device, a plate, a plurality of tubes cylindrical in cross section and open at their upper ends mounted on said plate for receiving articles generally the shape of the tube, means at the end of the tube for displaying an article in the tube and preventing it from being removed in a direction at right angles to the tube, but permitting removal of the article by its lower end being moved outwardly to incline it to the axis of the tube, and yielding fingers extending over a portion of the upper end of each tube to permit insertion of the articles but prevent their removal, said means also serving to mount said tube on said plate.

ALFRED OGDEN.
